ART OF CRACKING HYDROCARBONS

Willis S. Gullette, Highland, Ind., assignor to
Sinclair Refining Company, New York, N. Y.,
a corporation of Maine

Application December 16, 1929, Serial No. 414,381

3 Claims. (Cl. 196—61)

This invention relates to improvements in the cracking of heavier and higher boiling hydrocarbon oils for the production of lighter and lower boiling hydrocarbon oils in operations in which the heavier or higher boiling oil is heated to a high cracking temperature while in the vapor phase.

The invention is of special value and application in conjunction with operations of the type described in an application filed June 13, 1927, Serial No. 198,621, by Harry L. Pelzer, but the invention is also useful in broader application.

The invention provides particularly an improved operation in which corresponding constituents of raw stocks and recycled stocks are subjected to cracking conditions particularly advantageous with respect to the particular constituent and in which conditions in the operation are nevertheless maintained continuously uniform.

According to this invention, two separate streams of oil are flowed through two separate heating conduits and separately heated to high cracking temperatures in the vapor phase therein, the hot oil products discharged from these two heating conduits are separately subjected to scrubbing operations for the separation of tar and separated tar is discharged from these scrubbing operations, none of the discharged tar being returned as such to the heating conduits, the vapors from the two scrubbing operations are separately subjected to successive first and second fractionating operations in which constituents heavier or higher boiling than suitable as components of the desired product are condensed to form high boiling condensates, a cracked distillate product or products is condensed from the vapors escaping from the fractionating operations, and condensate from the two first fractionating operations is supplied to one of the two heating conduits and condensate from the two second fractionating operations is supplied to the other of the two heating conduits. The oil stream flowing through the heating conduit to which the condensate from the two second fractionating operations is supplied is advantageously heated to a higher temperature therein than is the oil stream flowing through the other heating conduit. These condensates may include, as will appear, together with constituents condensed from the hot oil products discharged from one or the other of the heating conduits, constituents of corresponding boiling range of raw stocks supplied to the operation. The condensate of relatively higher boil-

ing range, including the constituents within this boiling range produced in both heating operations, is thus subjected to conditions more appropriate to the cracking of these higher boiling high boiling constituents while the condensate of relatively lower boiling range, including constituents within this boiling range produced in both heating operations, is also subjected to conditions more appropriate to the cracking of these lower boiling high boiling constituents while at the same time, by dividing the heating operations as just described, the conditions in each of the separate heating operations may be maintained continuously uniform over prolonged periods of time although the conditions in the separate heating operations may differ one from the other.

The invention will be further described in connection with the accompanying drawing which illustrates, diagrammatically and conventionally, in elevation and partly in section and with parts broken away, one form of apparatus adapted for carrying out the process of the invention.

The apparatus illustrated comprises a pair of heating conduits 1a and 1b arranged in heating furnaces 2a and 2b, a pair of scrubbing towers 3a and 3b, a pair of fractionating towers 4a and 4b, another pair of fractionating towers 5a and 5b, a pair of treating towers 6a and 6b, still another pair of fractionating towers 7a and 7b, and a pair of condensers 8a and 8b and receivers 9a and 9b. Oil is supplied to the heating conduit 1a through connection 10 and to the heating conduit 1b through connection 11, the hot oil products from the heating conduits 1a and 1b are discharged into the scrubbing towers 3a and 3b respectively through connections 12a and 12b respectively, tar is discharged from the scrubbing towers 3a and 3b through connections 13a and 13b respectively, vapors escaping from the scrubbing tower 3a through connection 14a pass successively through the fractionating tower 4a, connection 15a and fractionating tower 5a and vapors escaping from the scrubbing tower 3b through connection 14b similarly pass successively through fractionating tower 4b, connection 15b, and fractionating tower 5b, the vapors escaping from the fractionating towers 5a and 5b may pass directly to the condensers 8a and 8b respectively or to these condensers through the treating towers 6a and 6b and the fractionating towers 7a and 7b respectively, and the cracked distillate product is discharged from the receivers 9a and 9b through connections 16a and 16b respectively.

In general the cracking operation may be carried out as described in application Serial No. 198,621 mentioned above. As illustrated, however, the digesting drums there described may be omitted and the hot oil products from the heating conduits may be discharged directly into the scrubbing towers. The heating furnaces may be arranged and operated, in general, as described in this mentioned application. The scrubbing towers may be arranged and operated, for example, as described in an application filed March 7, 1929, Serial No. 345,199, by E. C. Herthel. The refining towers and following fractionating towers may be arranged and operated, if used, as described in an application filed February 29, 1928, Serial No. 257,958, by E. C. Herthel. Liquefied polymers and associated constituents, higher boiling than suitable as components of the desired product, condensed in the fractionating towers following the refining towers may be returned to the scrubbing towers as described in an application filed February 29, 1928, Serial No. 257,945, by Arnold C. Vobach.

In carrying out the invention in the apparatus illustrated, the fractionating towers 4a and 4b are controlled to condense therein constituents of the same general boiling range to form corresponding relatively higher boiling condensates, and the fractionating towers 5a and 5b are similarly controlled to condense therein constituents of the same general boiling range to form corresponding relatively lower boiling condensates. The condensates separated in the fractionating towers 4a and 4b are combined and supplied, through connections 17a and 17b and connection 11, to the heating conduit 1b. Similarly, the condensates separated in the fractionating towers 5a and 5b are combined and supplied, through connections 18a and 18b and connection 10, to the heating conduit 1a. A part of these latter condensates may be discharged through connections 27a and 27b. The heating furnaces 2a and 2b are controlled, advantageously, so that the oil stream flowing through the heating conduit 1a is heated to a higher temperature therein than is the oil stream flowing through the heating conduit 1b.

In the production of motor fuel gasoline, for example, the heating furnace 2b may be controlled so that the hot oil products are discharged from the heating conduit 1b at a temperature in the neighborhood of 1100-1120° F. and the heating furnace 2a may be controlled so that the hot oil products are discharged from the heating conduit 1a at a temperature in the neighborhood of 1140-1160° F., the fractionating towers 4a and 4b may be controlled so that the temperature of the vapors escaping through connections 15a and 15b respectively approximates 425-500° F. and the fractionating towers 5a and 5b controlled so that the temperature of the vapors escaping therefrom approximates 375-450° F.

Fractionating towers 4a, 4b, 5a and 5b may be controlled by means of either or both of the groups of reflux condensers 19a, 19b, 20a and 20b, through which raw stock may be circulated as a cooling medium being at the same time preheated, and reflux condensers 21a, 21b, 22a and 22b, through which some extraneous cooling medium such as water may be circulated, or by means of the direct introduction of raw stock through connections 23a, 23b, 24a and 24b, or by means of such introduction of raw stock supplemented by the operation of one or more of the groups of

reflux condensers just mentioned. Scrubbing towers 3a and 3b may be controlled by means of the reflux condensers 25a and 25b or by the regulated introduction of raw stock through connections 26a and 26b or by means of such introduction of raw stock supplemented by the operation of the reflux condensers 25a and 25b.

Raw stock, particularly raw stock including tar or pitch constituents, may be supplied to the scrubbing towers 3a and 3b through connection 10 26, the high boiling oil components of such stock being vaporized in the scrubbing towers to be condensed in one or the other of the successive fractionating towers to be supplied therefrom to the connected heating conduit 1a or 1b. Relatively higher boiling raw stock corresponding to the condensate separated in the fractionating towers 4a and 4b or raw stock including lower boiling constituents may be supplied to the fractionating towers 4a and 4b through connection 15 23. Raw stock corresponding to the condensate separated in fractionating towers 5a and 5b may be supplied to these fractionating towers through connection 24. The same raw stock may be supplied through both connections 23 and 24 25 where the raw stock so supplied does not include any substantial amount of constituents higher boiling than suitable to be supplied to the heating conduit 1a. The fractionating towers 5a and 5b are with advantage controlled 30 so that the escaping vapors condense to form a distillate product of the desired boiling range or, if the fractionating towers 7a and 7b are used, of somewhat broader boiling range including a limited proportion of higher boiling constituents. 35

I claim:

1. In the cracking of hydrocarbon oils, the improvement which comprises flowing two separate streams of oil through two separate heating conduits and heating each stream of oil to a high cracking temperature in the vapor phase therein, separately subjecting the hot oil products discharged from the two heating conduits to scrubbing operations for the separation of tar and discharging tar therefrom, separately subjecting the vapors from the two scrubbing operations to successive first and second fractionating operations, condensing a cracked distillate from the vapors escaping from the fractionating operations, supplying the condensate from the two first fractionating operations to one of the two heating conduits and supplying the condensate from the two second fractionating operations to the other of the two heating conduits. 50

2. In the cracking of hydrocarbon oils, the improvement which comprises flowing two separate streams of oil through two separate heating conduits and heating the stream of oil in one of the heating conduits to a high cracking temperature in the vapor phase and the stream of oil in the other of the heating conduits to a higher cracking temperature in the vapor phase, separately subjecting the hot oil products discharged from the two heating conduits to scrubbing operations for the separation of tar and discharging tar therefrom, separately subjecting the vapors from the two scrubbing operations to successive first and second fractionating operations, condensing a cracked distillate from the vapors escaping from the fractionating operations, supplying the condensate from the two second fractionating operations to the heating conduit in which the oil stream is heated to the 70 75

higher temperature and supplying the condensate from the two first fractionating operations to the other of the two heating conduits.

3. In the cracking of hydrocarbon oils, the improvement which comprises flowing two separate streams of oil through two separate heating conduits and heating the stream of oil in one of the heating conduits to a high cracking temperature in the vapor phase and the stream of oil in the other of the heating conduits to a higher cracking temperature in the vapor phase, separately subjecting the hot oil products discharged from each of the two heating conduits to a separate scrubbing operation for the separation of

tar, separately supplying liquid oil to and discharging tar from each of the scrubbing operations, subjecting the vapors remaining after separation of the tar to first and second fractionating operations, condensing a cracked distillate from the vapors escaping from the fractionating operations, supplying the condensate from the second fractionating operations to the heating conduit in which the oil stream is heated to the higher temperature, and supplying the condensate from the first fractionating operations to the other of the two heating conduits.
